UNITED STATES PATENT OFFICE

92,060

DESIGN FOR A KEY RING OR SIMILAR ARTICLE

Lawrence E. Baer, Attleboro, Mass.

Application June 20, 1933, Serial No. 48,474

Term of patent 14 years

To all whom it may concern:

Be it known that I, LAWRENCE E. BAER, of Attleboro, in the county of Bristol and State of Massachusetts, have invented a new, original, and ornamental Design for a Key Ring or Similar Article, of which the following is a specification, reference being had to the accompanying drawing, forming part thereof.

Figure 1 is a front view of a key ring showing my new design;

Figure 2 is a side view of the same.

The essential feature of the invention resides in a circular ring-like body intersected by a circular panel which has convex faces, the panel

being surmounted by an eye of lesser diameter than that of the panel, and a pair of bars having rounded outer ends, the inner ends of which abut the panel and the undersides of which merge into the ring-like body adjacent to the panel, the overall length of the two bars being but slightly greater than the exterior diameter of the ring-like body.

I claim:

The ornamental design for a key ring or similar article, as shown and described.

In testimony whereof I have signed my name to this specification.

LAWRENCE E. BAER.
